US0D1016803S

(12) **United States Design Patent** (10) Patent No.: **US D1,016,803 S**
(45) Date of Patent: ** Mar. 5, 2024

(54) **NOTEBOOK COMPUTER**

- (71) Applicant: **SAMSUNG DISPLAY CO., LTD.**,
Yongin-si (KR)
- (72) Inventors: **Young Seok Kim**, Seoul (KR); **Han-Na Ma**, Suwon-si (KR); **Dong-Yeol Yeom**, Suwon-si (KR); **Chung Hui Lee**, Cheongju-si (KR)
- (73) Assignee: **Samsung Display Co., Ltd.**, Yongin-si (KR)
- (**) Term: **15 Years**
- (21) Appl. No.: **29/855,912**
- (22) Filed: **Oct. 7, 2022**

Related U.S. Application Data

- (62) Division of application No. 29/686,317, filed on Apr. 3, 2019, now Pat. No. Des. 969,798.

(57) **CLAIM**

The ornamental design for a notebook computer, as shown and described.

DESCRIPTION

FIG. 1 is a perspective view of the notebook computer, having an approximately rectangular sub-display (screen) being positioned at a top of a keyboard, and a touch pad being positioned in a middle of the keyboard;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the notebook computer that form no part of the claimed design.

1 Claim, 7 Drawing Sheets
